(57) **CLAIM**

The ornamental design for a combined toothbrush and flosser as shown and described.

DESCRIPTION

FIG. 1 is a front isometric view of a combined toothbrush and flosser showing my new design;

FIG. 2 is a rear isometric view thereof;

FIG. 3 is a right side elevation view thereof, the left-side elevation view thereof being a mirror image;

FIG. 4 is a front elevation view thereof;

FIG. 5. is a bottom plan view thereof; and,

FIG. 6 is a top plan view thereof.

The broken lines shown in the drawings are for the purpose of depicting portions of the article, and form no part of the claimed design.

1 Claim, 5 Drawing Sheets
